[57] CLAIM

The ornamental design for an articulated arm for a task light, as shown and described.

DESCRIPTION

FIG. 1 is a front, left side perspective view of an articulated arm for a task light showing our new design; FIG. 2 is a top plan view thereof on a reduced scale; FIG. 3 is a front elevational view thereof on a reduced scale; FIG. 4 is a rear elevational view thereof on a reduced scale; FIG. 5 is a left side elevational view thereof relative to the front of the arm on a reduced scale; FIG. 6 is a right side elevational view thereof relative to the front of the arm on a reduced scale; and, FIG. 7 is a bottom plan view thereof on a reduced scale. The task light head, table, and mounting clamps are shown in broken lines for illustrative purposes only and form no part of the claimed design.

FIG. 2.FIG. 3.FIG. 4.
